Primary Examiner — Darcey E Gottschalk(74) *Attorney, Agent, or Firm* — Handal & Morofsky LLC; Anthony H. Handal(57) **CLAIM**

The ornamental design for a bottle with pump as shown and described.

DESCRIPTION

FIG. 1 is a perspective view of a bottle with pump;

FIG. 2 is a perspective view thereof;

FIG. 3 is a perspective view thereof; and,

FIG. 4 is a top view thereof.

The dash-dot line in FIGS. 1-4 form no part of the claimed design, but were included in the original filing to indicate positions for the optional placement of labeling. The portions of the bottle visible within the dash-dot broken lines form part of the claim.
